UNITED STATES PATENT OFFICE.

CARL JULIUS MOHNS, OF CHEMNITZ, GERMANY, ASSIGNOR TO THE FIRM OF WANDERER FAHRRADWERKE VORM. WINKLHOFER & JAENICKE A. G., OF SCHÖNAU, NEAR CHEMNITZ, SAXONY, GERMANY.

MOUNTING OF THE PLATEN-ROLLER IN TYPE-WRITING MACHINES.

No. 829,929.

Specification of Letters Patent.

Patented Aug. 28, 1906.

Application filed August 11, 1904. Serial No. 220,402.

To all whom it may concern:

Be it known that I, CARL JULIUS MOHNS, of Chemnitz, Germany, have invented certain new and useful Improvements Relating 5 to the Mounting of the Platen-Roller in Type-Writing Machines, of which the following is a specification.

This invention relates to type-writing machines where the platen-roller is moved vertically from a lower to an upper position, or vice versa, in order to receive upon the paper thereon the impression of the respective characters of two sets of type.

The object of the invention is to provide 15 means whereby such upper and lower positions of the platen may be accurately and easily adjusted or set at any time to insure effective and uniform printing and true alinement. This is attained by mounting the 20 bearings of the platen-roller in vertical guiding-slots which are closed at the upper and lower ends and fitted at such ends with set-screws or the like, which limit the movements of the bearings and can be easily 25 adjusted at any time.

Referring to the accompanying drawings, Figure 1 is a sectional view with parts of the left bearing broken away. Figs. 2 and 3 are respectively an end view and plan, partly in 30 section, of a paper-carriage arranged according to the invention. Figs. 4 and 5 are detail views.

In carrying out the invention according to one modification the spindle *b* of the platen- 35 roller *A* is journaled in bearings *c* of the platen-frame *D*, such bearings being adapted to slide vertically in slots in the paper-carriage *E*. These slots are closed at the top and bottom ends, which are fitted with set- 40 screws *f f'*, having lock-nuts *g g*. To facilitate insertion of the frame *D* in the paper-

carriage, the bearings *c* are preferably secured to the frame by screws *d'*.

In the lower position of the frame *D* and platen-roller *A* the bearings *c* rest on the 45 lower set-screws *f*, while when the frame and platen are raised vertically, as indicated by the arrow, the bearings *c* strike against the upper set-screws *f'*. The arrangement and 50 easy accessibility of the set-screws thus afford when assembling or at any time a very simple, rapid, and accurate setting of the platen-roller, and therefore enable neat printing and accurate alinement to be maintained.

To place the platen *A* and its frames *D* in 55 position in the frame *E*, it is simply necessary to remove one of the bearings *c* by taking out the screws *d'*, then placing the other bearing in its proper slot in the frame *E* and bringing the opposite frame *D* flush with the opposite 60 slot, placing the detached bearing *c* in said slot and against the frame *D*, and finally screwing the bearing to its frame *D*.

Having now particularly described and ascertained the nature of my said invention 65 and in what manner the same is to be performed, I declare that what I claim is—

The combination in a type-writer, of a carriage having vertical slots at each end thereof, bearing-blocks movable in said slots, set-screws at each end of the slot for regulating the movement of the blocks, a platen-frame 70 removably secured to the blocks, and a platen having its axle bearing in said frame and the blocks, substantially as described.

In witness whereof I have hereunto set my hand in presence of two witnesses.

CARL JULIUS MOHNS.
